COMBINED MULTILIGHT INCANDESCENT LAMP AND SWITCH

Alfred F. Bahlke, Scotch Plains, N. J., assignor to Utility Electric Corp., Newark, N. J., a corporation of New Jersey

Application October 24, 1938, Serial No. 236,613

1 Claim. (Cl. 176—27)

Many incandescent electric lamps today are manufactured with a plurality of filaments of different wattages related and combined with each other so that they may be placed in the electric circuit either separately or all together so as to secure at will illumination of varying degrees of intensity. The invention relates particularly to "multilight" lamps wherein each filament has the same characteristics as that of an ordinary one filament lamp of the same wattage, as distinguished from the old so-called "turn-down" lamps having two filaments so related that when they are connected in series one will glow while when one is short-circuited the other will glow.

A prime object of my invention is to produce such a combined multilight incandescent electric lamp and switch that shall embody novel and improved features of construction, whereby the combination shall be simple and inexpensive and reliable and durable.

Another object is to provide a combination of the character described wherein all of the switch parts shall be mounted on the exterior of the lamp for easy assembly and for easy access for operation.

Other objects are to provide a combined electric incandescent lamp and switch wherein the switch shall include an operating ring rotatable coaxially with the lamp so that the switch can be easily reached and operated; and to obtain other advantages and results as will be brought out by the following description in conjunction with the accompanying drawings, in which:

35 Figure 1 is a side elevation of a combined electric incandescent lamp and switch.

Figure 2 is a horizontal sectional view on an enlarged scale, taken on the line 2—2 of Figure 1.

40 Figure 3 is a similar view taken on the line 3—3 of Figure 1.

Figure 4 is a vertical sectional view taken on the line 4—4 of Figure 2, the lamp bulb or envelope being shown in side elevation.

45 Figure 5 is an enlarged fragmentary horizontal sectional view showing the connection of one of the switch contacts to the shell terminal of the lamp base.

Figure 6 is a similar view showing the connection to the shell terminal of one of the switch contacts for the lamp filaments.

Figure 7 is a vertical sectional view on the line 7—7 of Figure 3 with the lamp bulb and base shown in side elevation.

50 Figure 8 is a vertical sectional view on the line

8—8 of Figure 3, on a further enlarged scale, and Figures 9, 10, 11 and 12 are wiring diagrams showing the operations of the switch for controlling the circuits through the filaments of a multilight lamp.

Specifically describing the invention, the reference character A designates the usual glass bulb or envelope of an incandescent lamp within which is mounted a plurality of filaments B and C which have a common terminal D and individual 10 terminals E and F respectively. Generally, the two filaments B and C are of different wattage, and in accordance with the invention are energized either individually or together as may be desired.

The lamp also includes a base G which is of generally known construction including an outer screw threaded conducting shell terminal 1 to be screwed into an electric lamp socket, and a central terminal 2. The common terminal D of 20 the filaments B and C is permanently connected to one of the terminals of the base, in the present instance the terminal 2. In accordance with the invention, a switch for controlling the circuits through the filaments B and C is mounted on 25 the base G, preferably exteriorly thereof.

As shown, a switch contact is provided for the respective terminals E and F of the filaments B and C, and for convenience these switch contacts are designated 3 and 4. The contacts are 30 identical and each comprises a spring strip 5 one end of which has an opening 6 through which passes a hollow rivet or other suitable fastening means 7 for connecting the contact to the base shell terminal 1 adjacent the bulb A. 35 Each of the contacts 3 and 4 is insulated from the shell terminal 1 by fiber or other suitable bushings 8. Preferably the contacts 3 and 4 are spaced circumferentially of the shell terminal as clearly shown in Figure 3.

Other similar contacts 9 and 10 are electrically connected to the shell terminal 1 by rivets 11, there being no insulating bushings between the rivets 11 and the shell terminal and contacts. These contacts 9 and 10 are also preferably spaced 45 circumferentially of the shell terminal and in approximately the same plane with the contacts 3 and 4 that is normal to the axis of the shell terminal.

The various contacts 3, 4, 9 and 10 cooperate 50 with a switch operating member that is shown in the form of a sectional ring H of insulating material which is rotatably mounted on the base G. Preferably the ring is mounted to rotate coaxially with the base in overlying relation to 55

the contacts 3, 4, 9 and 10 and the ring is formed of two approximately semi-circular or sector-shaped complementary sections that are applied to the base in the general plane normal to the 5 axis of the base. The sections are separably connected together by any suitable means such as a metal split spring ring 12 seated in an exterior circumferential groove 13 in the ring. The interior surface of the ring H has a groove 10 14 which is of a width and depth to freely receive the riveted ends of the contacts as shown in Figures 3 and 8, and in the base of the groove 14 is a second groove 15 of a width to freely slidably receive the reduced contacting ends of 15 the contacts 3, 4, 9 and 10. With this construction, the contacts are entirely housed and concealed within the ring, and hold the ring against axial movement longitudinally of the base.

In the groove 13 of the operating ring H is a 20 segmental conductor 16 which as shown is substantially equal in length to one of the sections of the ring, said conductor serving to electrically connect the filament contacts 3 and 4 with the shell 1 through the contacts 9 and 10, upon 25 rotation of the ring H. The contact strips are of resilient nature so as to constantly maintain spring frictional contact with the base of the groove 15 or the conductor 16.

The contacts 3, 4, 9 and 10 are so spaced and 30 the length of the conductor is so related to the spacing of the contacts as to insure that at least one of the contacts 9 or 10 and either one or both of the contacts 3 and 4 may at the same time engage the conductor 16, whereby the filaments B and C may be energized either individually or together, or both filaments may be completely deenergized. In operation, referring to Figure 9, the ring H is so positioned that the conductor 16 engages only the contacts 9 and 10 so that both filaments B and C are deenergized. In Figure 10, the conductor 16 engages the contact 10 and the contact 3 whereby only the filament B is energized, while in Figure 11 the conductor 16 engages both of the contacts 3 40 and 4 and the contact 9 so that both filaments B and C are energized. Figure 12 shows the conductor 16 engaging the contact 9 and the contact 4 so that only the filament C is energized.

It will be observed that the switch can be easily operated by simply gripping the ring H between the thumb and index finger of one hand and rotating the ring coaxially with the base. To facilitate this action, the ring may have separated or roughened surfaces 17, and the outer periphery of the ring may be polygonal. Preferably the ring H is rotatable in the same direction that the lamp is screwed into a socket, so that rotation of the switch ring will not loosen 10 or unscrew the lamp in the socket. If desired, suitable means may be provided for positively preventing rotation of the ring in the opposite direction.

Obviously the details of structure of the lamp 15 and switch, the number of filaments, and the number and arrangement of the switch contacts, may be widely modified and changed by those skilled in the art without departing from the spirit or scope of the invention.

Having thus described my invention, what I claim is:

A combined multi-filament electric incandescent lamp and switch, comprising a base having a shell terminal and a central terminal, a 25 bulb, a plurality of filaments in said bulb, and means for energizing said filaments selectively, individually and together, including a direct common electrical connection between one terminal of each of said filaments and said central terminal of the base, a plurality of contacts mounted exteriorly on said shell terminal in spaced relation circumferentially thereof, certain of said contacts being electrically insulated from said shell terminal with one thereof electrically connected to the other terminal of each filament, and at least one other of said contacts being directly electrically connected to said shell terminal, and a switch operating-ring rotatable coaxially on said base exteriorly thereof and having a conductor to electrically connect selectively individually and together the first mentioned contacts to the second mentioned contact upon rotation of said switch operating ring in one direction.

ALFRED F. BAHLKE.
